INKING PAD

Winfred G. Mittag, Ridgewood, N. J.

Application November 24, 1937, Serial No. 176,149

4 Claims. (Cl. 91—54.5)

This invention relates to improvements in inking pads, the principal object of the invention being to provide an inking pad having an ink reservoir for automatically supplying ink to the pad thereby to maintain the same in evenly inked condition throughout the life of the pad.

A further object of the invention is to provide an inking pad having means for distributing over a comparatively large area a supply of ink delivered to the pad at a single point.

Other objects and advantages of the invention will appear as the description proceeds.

In the drawing accompanying this specification,

Fig. 1 is a plan view of the outer or cover section of the pad frame;

Fig. 2 is a plan view of the inner or base section of the pad frame and showing the ink reservoir in place therein;

Fig. 3 is a transverse sectional view taken approximately on the line 3—3 of Fig. 1;

Fig. 4 is a side view of the base section shown in Fig. 2;

Fig. 5 is a transverse sectional view, on an enlarged scale, through the completely assembled pad;

Fig. 6 is a reverse plan view of the base section; and

Fig. 7 is a plan view, partly broken away, of the pad proper, one thickness of felt being removed to disclose the ink-equalizer.

Referring to the drawing, the frame of the pad comprises a base member and a cover member, both of which members may be made of wood, metal, glass, Bakelite, rubber or any material that may be found suitable or convenient. I prefer to use a material having a fair degree of elasticity.

The base member comprises a disk 1 of substantial thickness having a centrally disposed cylindrical depression extending inward from its top surface and forming a chamber 2 for the reception of the ink reservoir to be hereinafter described. For the sake of lightness and flexibility the base member may be recessed at its underside to form a plurality of chambers 3 disposed around the lower portion of the wall of chamber 2, the said chambers 3 being separated from each other by radially extending walls 4 connecting the wall of chamber 2 with the outer annular wall 5 surrounding the chambers 3, as shown in Fig. 6. The annular wall 5 is provided at its outer surface with a plurality of radially extending lugs 6 and with L-shaped recesses 7 adjacent said lugs for cooperation with similar

formations on and in the cover member thereby to lock the members together as hereinafter described. The base member is further provided at its top side with an annular lip or rim 8 and a small annular depression 9 to accommodate the edge of the pad proper.

The cover member of the frame comprises an annular wall 10 having an inturned flange 11 at its upper end, and an annular bead 12 on the top surface of said flange. At its inner surface the wall 10 of the cover member is provided with inwardly projecting lugs 13 and with L-shaped recesses 14 contiguous to said lugs. The respective lugs and recesses of the cover and base members are so disposed that the base member may be readily inserted into the cover member by causing the lugs of each of said members to enter the vertical portions of the recesses of the other member and then, by twisting or slightly turning the base member with relation to the cover member the lugs of each member will pass into the horizontal portions of the recesses in the other member, said lugs and recesses thus forming a sort of bayonet connection for securely locking the members together but permitting their ready separation when necessary.

The invention, as hereinbefore stated, comprehends a special form of ink reservoir which will automatically maintain a regular supply of ink to the pad. As herein shown the reservoir comprises receptacle 15 of such diameter that it will fit within the chamber 2 of the base member. The upper end of the receptacle is closed by a cap 16, said cap having a depending tube 17 secured in a hole at the center of the cap and extending downward to a point slightly above the bottom of the receptacle. Upon the top surface of the cap 16 is supported a flexible diaphragm 18, preferably of rubber, having an annular flat portion and a central spherical portion at the center of which is formed a small perforation or pin hole in axial alignment with the tube 17. The diaphragm is held in place by a clamping cap member 19 the center of which is cut out so as to expose the spherical portion of the diaphragm. The skirt portion of cap member 19 fits snugly around the corresponding skirt of cap member 16 while the horizontal portion of cap member 19 impinges on the flat portion of the diaphragm, thereby clamping the latter between the two cap members.

The present invention also comprehends the provision of an ink-spreading or equalizing element for use in connection with the ink pad for cooperation with the reservoir above described

to cause an even distribution of the ink throughout the pad. In the drawing the pad is shown as comprising a pair of disks 20, 21 of any suitable thin textile fabric of good wearing quality, between which disks are disposed a pair of felt disks 22, 23. The equalizing member above referred to consists of a disk 24 of a moisture resisting fabric disposed between the felt disks. I have found by practical tests that a material such 10 as oil silk is particularly well suited for this purpose. However, I do not wish to limit my invention to this specific material, since any thin material having moisture-and wear-resisting qualities will serve the purpose. The disk 24 is provided with a number of perforations 25 distributed over the area of the disk except at its center portion, which will directly overlie the spherical portion of the diaphragm 18. The disks 20, 21, 15 22, 23 and 24 are all secured together by an edge-binding strip 26 of channel form in cross-section 20 and having its edges bent inward so as to grip the disks and fasten them together.

Before assembling the device, a supply of ink is placed in the receptacle 15 and the diaphragm 25 18 secured in position by the cap member 16. The reservoir thus assembled is inserted in the chamber 2 of the base member, and the ink pad above described placed over the reservoir. The base member is then placed within the cover 30 member 10 and given a slight turning movement as hereinbefore described, thus locking the base and cover members together and at the same time clamping the edge of the ink pad between the flange 11 of the cover member and the depression or groove 9 in the top surface of the base member. As shown in Fig. 5, the top of the ink reservoir extends somewhat above the top of the chamber 2, so that when the members are locked together as shown in that figure the center portion of the pad will impinge upon the 35 diaphragm 18, thus normally closing the pinhole in the diaphragm.

From the foregoing it will be readily seen that the pressure of a stamp on the pad will depress the diaphragm 18 thus forcing the air between the diaphragm and ink reservoir to pass out through the pinhole vent in the diaphragm, and upon release of such pressure a vacuum will be created between the diaphragm and ink reservoir 40 whereby ink will be drawn up through the tube 17 and upon the next depression of the diaphragm will be discharged through the diaphragm vent on to the lower fabric and felt disks 21 and 23, which of course will absorb said ink. 45 When the disks have once become wet by this operation, a certain amount of capillary action is set up which, by reason of the small diameter of the tube, causes the ink to be continuously fed to the disks so long as the stamp pad is in operation. However, upon discontinuance of operation there will be a slow leakage of air through the disks, gradually filling the space between the diaphragm and the cap 16, thus restoring the 50 remaining ink to its normal level in the tube. 55 Were it not for the equalizing disk 24, after a number of strokes of the stamp on the pad, the ink would pass freely through all of the disks and eventually the center portion of the pad would be saturated while the portions remote from the center would remain comparatively dry. 60 65 By the provision of the equalizer, however, the ink at the center of the lower disk 23 encounters

resistance to its passage by reason of the solid center of the equalizing disk and is deflected thereby toward the perforations 25 in said equalizing disk, through which perforations it passes to the upper disks. It will thus be seen that whereas the ink is delivered to a single central point of the lower disk, it reaches the upper disk at a plurality of widely separated points so that the ink is evenly distributed over the surface of the topmost disk. 10

It will be evident that the present invention, by automatically supplying ink to the pad, eliminates the messy job of re-inking the pad by hand. Moreover the device affords the advantage that the ink reservoir and the pad can be supplied 15 as separate units so that those elements can be renewed without the necessity of replacing the entire device.

Having thus described my invention what I 20 claim is:

1. A device of the character described, comprising in combination, a base member, an ink receptacle supported in said base, a stamp pad disposed above said receptacle, and means forming an air chamber between said pad and receptacle, said means being operative upon depression and release of the pad to create a vacuum in said chamber thereby to extract ink from the receptacle and discharge it upon the pad. 25

2. The combination with a stamp pad, of an ink receptacle provided with a cap for closing the receptacle, a tube mounted in said cap and communicating at one end with atmosphere and at the other end with a plane near the bottom of the receptacle, a flexible diaphragm disposed 35 between said pad and said cap, said diaphragm having a vent perforation in communication with said tube and normally closed by the pad whereby on depression and release of the pad a vacuum will be created between the diaphragm and tube 40 thereby to extract ink from the receptacle and deliver it to the pad.

3. A device of the character described comprising in combination, an ink receptacle having a closing cap, a stamp pad disposed above said cap, flexible means between said pad and receptacle for forming an air chamber above the receptacle, said means being operative upon depression and release of the pad to create a partial vacuum in said chamber, and a tube of restricted diameter communicating at one end with said chamber and at its lower end with the ink receptacle near the bottom thereof. 45

4. The combination with a stamp pad, of an ink receptacle provided with a cap for closing the receptacle, a tube mounted in said cap and communicating at one end with atmosphere and at the other end with a plane near the bottom of the receptacle, a flexible diaphragm disposed between said pad and said cap, said diaphragm having a spherical portion disposed centrally thereof in overlying relation to said tube and the center portion of said cap thereby forming an air chamber between the diaphragm and tube, said spherical portion having a vent perforation 60 in communication with said tube and normally closed by the pad whereby on depression and release of the pad a vacuum will be created between the diaphragm and tube thereby to extract ink from the receptacle and deliver it to the pad. 65
